HOMOGENIZER

Bernard Feldmann, Rehovoth, Israel

Application February 27, 1951, Serial No. 213,023
In France March 31, 1950

2 Claims. (Cl. 259--4)

1

This invention relates to homogenizers for use in the preparations of emulsions of liquids non-miscible with one another, pastes, etc., and more particularly to homogenizers of the kind wherein two or more substances of different specific gravity in the form of liquids, pastes or suspensions of solids in liquids are intimately mixed in, and ejected through, an annular conical orifice.

In some known homogenizers of the kind referred to the annular conical orifice is formed between male and female conical members one of which is rotated during the operation. In another known kind the annular conical orifice is formed between male and female conical members one of which is applied against the other one by spring pressure, and lifted therefrom only temporarily under the impact of the matter to be homogenized which is fed to the homogenizer under pressure. Apparatus of both kinds include, among the essential constituent parts of the homogenizing system, members that are movable, and are in fact in movement, in the normal operation of the apparatus.

This invention has the object to provide a homogenizer with annular conical homogenizing orifice wherein the elements of the homogenizing system proper remain immovable during the operation, with a view to rendering the apparatus less liable to wear and tear, making it easy to clean and capable of homogenizing, without clogging, such particles in liquid suspension as have undergone a superficial preliminary mixing only, and enabling the apparatus to run at high speed on very little power.

The invention consists in a homogenizer comprising an annular conical orifice defined between male and female conical members arranged to remain motionless in the normal operation of the homogenizer, and a feed channel including one or more spiral guide members leading to said orifice.

It is preferred to make at least one of the conical members axially adjustable for allowing variation of the width of the conical orifice.

The matter to be homogenized is forced under pressure into the feed channel where it undergoes preliminary intimate mixing and is imparted a spirally rotating motion with which it enters the homogenizing system proper, i. e. the annular conical orifice between the stationary male and female conical members. Variation of the particle size of the homogenized mixture is obtained by adjustment of the width of the orifice. Where a rotary pump of the intermeshing type is used for feeding the matter to the homogenizer a fur-

ther preliminary mixing step is added to the homogenizing operation which improves the homogenization and decreases the required feeding pressure and power consumption.

5 A homogenizer according to the invention is illustrated, by way of example only, in the accompanying drawing which shows an axial section thereof, it being understood that the invention can be carried out in practice in many different forms.

10 The apparatus here illustrated by way of example comprises an oblong main body 1, e. g. of cylindrical form, having a throughgoing bore including three sections, namely, a delivery chamber 2 at one end, a tapped median part 3 which accommodates the homogenizing system proper and is, therefore, referred to as homogenizing chamber, and a feed channel 4. The latter opens into a tubular socket 5 which is internally threaded for connection with the feeding pipe (not illustrated). The chamber 2 is sealed by a lid formed by a plug 6 made integral with a boss 7. A spindle 8 extends through the body 1 and boss 7 out of the latter and carries on its projecting end a handle 9. The joint between the spindle and boss is tightened by a gland 10. The bore of the plug 6 and boss is tapped for the reception of a threaded length 11 of the spindle. A plug 12 is screwed into the homogenizing chamber 3. It has an axial bore bounded by two female conical surfaces which merge into one another with their narrower ends while their wider ends lead, respectively, to the delivery chamber 2 and to the end of the homogenizing chamber 3 adjoining the feed channel 4. Within the conical part of the bore adjoining the delivery chamber the spindle is made integral with a conical body 13, an annular conical orifice 14 being defined between the surfaces of parts 12 and 13 which latter constitute the female and male members, respectively, of the homogenizing system proper. The width of the orifice 14 can be varied by axial displacement of the spindle produced by screwing it up or down. The part of the spindle located in the feed channel is made integral with one or more spiral guide ribs 15. Finally an outlet 16 for the homogenized matter is laterally branched off from chamber 2.

15 The matter to be homogenized, which may be collected in a suitable feeding funnel or the like (not shown) is forced by means of any suitable injector or pump (not shown either) into the feed channel and through the spiral ducts defined by the rib or ribs 15 where it undergoes a preliminary intimate mixing and is imparted a

spirally rotating movement with which it enters the conical bore of plug 12 adjoining the feed channel where it is given a centripetal rotary flow into the conical homogenizing orifice 14. From the latter the homogenized mass leaves through the delivery chamber 2 and outlet 16.

The foregoing description shows that the homogenizer according to the invention is of extreme simplicity and robustness which enables it to perform under conditions of high endurance. For cleansing the spindle and plug 12 can easily be dismounted.

I claim:

1. A homogenizer comprising an oblong main body with through-going cylindrical bore including three coaxial sections, said sections constituting a feed channel, an internally threaded homogenizing chamber of larger diameter than the feed channel, and a delivery chamber of larger diameter than the homogenizing chamber; a plug closing the body at the end adjoining the delivery chamber and having a tapped bore coaxial with the bore of the body; a spindle extending through the bores of the body and plug projecting out of the plug, a handle on the projecting portion, the spindle including a threaded length screwed into the tapped bore of the plug; a second plug including a conical female surface coaxial with the bore of the body screwed into the homogenizing chamber; at least one spiral guiding rib made integral with the portion of the spindle located inside the feed channel; a conical male member on the portion of the spindle adjacent the guiding rib and located inside the homogenizing chamber for cooperation with said female surface; and a lateral outlet branched off from the delivery chamber.

2. A homogenizer comprising an oblong main body with through-going cylindrical bore including three coaxial sections of different width,

said sections constituting in sequence a feed channel, an internally threaded homogenizing chamber of larger diameter than the feed channel, and a delivery chamber of larger diameter than the homogenizing chamber; a plug closing the body at the end adjoining the delivery chamber and having a tapped bore coaxial with the bore of the body; a spindle extending through the bores of the body and plug and projecting out of the plug, a handle on the projecting portion, the spindle including a threaded length screwed into the tapped bore of the plug; a second plug screwed into the homogenizing chamber and having an axial bore bounded by two female conical surfaces merging into each other with their narrower ends and leading at their wider ends, respectively, to the delivery chamber and to the end of the homogenizing chamber adjoining the feed channel; at least one spiral guiding rib made integral with the portion of the spindle located inside the feed channel; a conical male member on the portion of the spindle adjacent the guiding rib and located inside the homogenizing chamber for cooperation with the female conical surface leading to the delivery chamber, and a lateral outlet branched off from the delivery chamber.

BERNARD FELDMANN.
